UNITED STATES PATENT OFFICE

116,559

DESIGN FOR A GAME DEVICE

Henry A. Fisher, Parkersburg, W. Va.

Application July 5, 1939, Serial No. 85,854

Term of patent 3½ years

To all whom it may concern:

Be it known that I, Henry A. Fisher, a citizen of the United States, residing at Parkersburg, county of Wood, State of West Virginia, have invented a new, original, and ornamental Design for a Game Device, of which the following is a specification, reference being had to the accompanying drawing, forming a part thereof.

In the drawing:

I claim:

The ornamental design for a game device, substantially as shown.

HENRY A. FISHER.
